L. A. HOLLWITZ

RADIO BULB SOCKET

Filed Oct. 26, 1926

UNITED STATES PATENT OFFICE.

LUDWIG A. HOLLWITZ, OF BROOKLYN, NEW YORK.

RADIO BULB SOCKET.

Application filed October 26, 1926. Serial No. 144,386.

This invention relates to sockets for radio bulbs and the like apparatus. More particularly this invention is directed to a socket of improved construction having novel means 5 for securing the bulb in the socket and for making the electrical joint between the bulb terminals and the socket contacts efficient to a high degree.

An object of the invention is the provision of a socket of the character described having manual operated means for positively clamping the bulb terminals to the socket contacts to hold the resulting electrical connection against possible disarrangement. 15 The socket embodying the invention is adapted for ordinary use and has been found to give satisfactory service under the severest conditions of operation, as for example, when used on equipment which is mounted 20 on moving vehicles.

A further object of the invention is the provision of an improved socket of the character described constructed of few and simple parts, which is cheap to manufacture and 25 practical for the purposes described.

Other objects of this invention will in part be obvious and in part hereinafter pointed out.

The invention accordingly consists in the 30 features of construction, combination of elements and arrangement of parts which will be exemplified in the construction hereinafter described and of which the scope of application will be indicated in the following 35 claims.

In the accompanying drawing in which is shown one of the various possible illustrative embodiments of this invention—

Fig. 1 is a cross-sectional view of a socket 40 embodying the invention taken on lines 1—1 in Fig. 2;

Fig. 2 is a plan view of my improved socket;

Fig. 3 is a plan view of the socket base 45 member.

Fig. 4 is a sectional view of the socket intermediate member; and

Fig. 5 is a fragmentary cross-sectional view of a modified form of socket embodying the invention.

Referring in detail to the drawing, 10 denotes a socket embodying the invention which is adapted to receive the base 11^a of a bulb 11 of any well known construction, having 55 a plurality of terminal pins 11^b, for exam-

ple, a radio bulb having four pin terminals, as shown in dotted lines in Fig. 1.

The socket 10 is seen to comprise three non-current carrying parts, namely, a base 12, a holder 14, in which the base 11^a is 60 mounted and an intermediate or clamp-control member 13 rotatably held between the base 12 and the holder 14. Said parts may be made of any suitable material but are preferably formed of a molded insulating compound, such as "bakelite" or the like material.

To receive the bulb terminal pins 11^b, metallic receptacle contact members 15 are provided, which extend up from the base 12 70 into the holder 14 and are disposed in spaced relation to correspond with the positioning of the pins 11^b on the bulb base 11^a.

The upper or receiving end of the member 15 is provided with radial slots 15^a, extending longitudinally of said member a substantial distance down from said contact ends, and forming a plurality of gripping portions 15^b on each member 15. The outer surface 15^c of the member 15 may have a downwardly 80 converging taper, said surface 15^c extending through correspondingly shaped passages in the bottom of holder 14, as shown in Fig. 1, thus retaining the socket parts from separation and serving as a portion of the clamping contacting means as will hereinafter appear.

The base 12 may be of a dished construction so as to provide a hollow bottom wherein current carrying connections are disposed. 90 These connections comprise usual leads or jumpers 16, each of which is secured at one end in any suitable manner as by riveting to the lower end of contact 15, said leads 16 being radially disposed and anchored 95 at their other ends by terminal screws 17; these latter are arranged to extend up through the rim portion of the base 12 to the upper exterior side as shown in Figs. 1 and 2. The free end of the screws 17 may 100 be provided with knurled nuts 18 to form binding posts, which for a four terminal radio bulb may be marked in the usual manner G, P, F— and F+ as shown in Figs. 1 and 2.

A dominant feature of the invention is the provision of manually operated clamping contact means for positively effecting a gripping action of the terminal pins 11^b, between the receptacle contact portions 15^b. Said 110

means is seen to comprise a series of wedges or cam projections 12^a which are constructed to form a circular structure 12^b, said structure being preferably made integral with the base 5 12 as shown in Figs. 1 and 3.

The clamp-control member 13 is mounted to rotate over the projections 12^a on the structure 12^b and is annular shaped to permit passage of the contact member 15 through its 10 central opening 13^a. Corresponding with the structure 12^b and projections 12^a, there is provided on the under side of member 13 a series of recesses as shown in Figs. 1 and 4.

To provide a non-slip finger gripping 15 means on member 13, the rim surface 13^c thereof may be serrated or knurled in the well known manner.

In using the invention, the socket 10 is secured in place by any suitable fastening 20 means such as screws (not shown) passing through holes 12^c provided in the base 12. The clamp control member 13 is then rotated counter-clockwise (as seen on Fig. 2) until said member is in its lowermost position, that 25 is, when the recesses 13^b are positioned so as to be occupied by the projections 12^a. The bulb base 11^a may now be inserted into the holder 14, the terminal pins 11^b being guided to their proper receptacle contact members 30 by the aid of the usual slot 14^a on the upper rim of the holder. After the terminal pins 11^b have been entered between the gripping portions 15^b of the contacts 15 as shown in Fig. 1, the clamp control member 13 is rotated clockwise, which causes the said member to rise due to camming or wedging action 35 of the projections 12^a in the recesses 13^b. The holder 14 and the member 13 are lifted with respect to the base and the tapered openings 40 in the holder bottom 14 surround the gripping portions 15^b are caused to engage the tapered surfaces 15^c of the contacts 15 compressing same about the terminal pins 11^b thus assuring a positive clamping connection which is mechanically and electrically 45 efficient to a high degree.

To remove the bulb the member 13 is simply rotated counter-clockwise which releases the terminal pins 11^b from the grip of 50 the contacts 15 and the bulb 11 may be lifted out of the holder.

In Fig. 5 is shown a socket 10^a of modified construction embodying the invention. The receptacle contact members 25 are here seen 55 to be formed of tubular material so that the lower ends 25^d may be riveted over in eyelet fashion. In order to insure a positive release control about the gripping portions 25^b of the contacts 25, recesses 14^c in the holder 60 bottom 14^b and tapered collars 26 on the end portion of the contacts 25 are provided in place of the tapered openings in the holder 14 shown in Fig. 1, said collars 26 being supported in the recesses 14^c on compression 65 springs 27.

It is also apparent from Fig. 5 that the resilient spring construction of the clamping means about each set of contact gripping portions 25^b, takes care of inequalities in the diametral sizes of the bulb terminal pins 11^b, 70 should these vary from the normal standard size by permitting each set of said gripping portions to be independently contracted.

It will thus be seen that there is provided a device in which the several objects of the 75 invention are achieved and which is well adapted to meet the conditions for practical use.

As various possible embodiments might be made of the above invention and as various 80 changes might be made in the embodiment above set forth, it is to be understood that all matter herein set forth or shown in the accompanying drawing, is to be interpreted as 85 illustrative and not in a limiting sense.

Having thus described my invention, I 90 claim as new and desire to secure by Letters Patent:—

1. A socket of the character described comprising a plurality of non-current carrying 95 parts and contacts each having gripping members forming an inwardly tapered structure and supported on one of the parts, another of the parts being mounted for outward movement with respect to the last mentioned 100 part for releasably controlling the gripping action of said members.

2. A socket adapted to receive a bulb having pin terminals comprising a base, a holder adapted to receive the bulb, contacts 105 mounted on said base and extending into the holder for engaging with the bulb terminals and manually controlled means mounted between the base and holder for releasably clamping said contacts to the bulb terminals. 110

3. A socket having a holder and contacts adapted to receive the base and terminals respectively of a radio bulb, said contacts having gripping members and means for moving the holder with respect to said contacts for clamping said members to the bulb terminals. 115

4. A socket adapted to receive a bulb having pin terminals, comprising a base, contacts mounted on said base, the receiving ends 120 of the contacts being formed with gripping portions extending through the top of the base adapted to engage with the bulb terminals, a member engaging the said gripping portions, and wedging means interposed between said member and base to clamp the said portions to the pin terminals of the bulb.

5. In a socket of the character described, a receptacle contact having gripping members each forming an inwardly tapered split 125 frusto-conical structure adapted to receive a pin terminal of a bulb, and resilient means surrounding said structure for releasably applying pressure to clamp said members about said terminal. 130

6. A socket adapted to receive a bulb having pin terminals, comprising a base, a holder adapted to receive the bulb, contacts mounted on said base, the receiving ends of the contact being formed with gripping portions and extending into the holder for engaging with the bulb terminals, spring

pressed collars engaging said contact gripping portions supported by the holder and a control member for wedging the said gripping portions in the holder to clamp the said portions to the pin terminals of the bulb. 10

In testimony whereof I affix my signature.
LUDWIG A. HOLLWITZ.
